MANUFACTURE OF HYPOSULPHITES

Oswin Nitzschke and Ulrich Kopsch, Leverkusen-I. G. Werk, Germany, assignors to I. G. Farbenindustrie Aktiengesellschaft, Frankfort-on-the-Main, Germany

Application September 13, 1938, Serial No. 229,706
In Germany May 10, 1938

4 Claims. (Cl. 204—9)

This invention relates to the manufacture of water-soluble hyposulphites, more particularly to the manufacture of sodium hyposulphite by cathodic reduction of bisulphite-containing solutions.

5 It is known to prepare hyposulphites, for instance, alkali- or alkaline-earth metal hyposulphites by electrolyzing bisulphite-containing solutions as catholyte in an electrolyzing cell which is divided into an anode and cathode 10 chamber by means of a diaphragm.

Since hyposulphite solutions tend to a quick decomposition this process causes many difficulties, so that up to the present day no technical manufacture of hyposulphites by cathodic reduction of bisulphites is realized. Though many 15 investigators have studied the conditions which are to be observed for obtaining concentrated solutions of hyposulphites with satisfactory current and bisulphite yields, no commercial process has been developed. So Frank, who has used sodium 20 bisulphite as catholyte and NaCl, H₂SO₄ or NaOH as anolyte, obtained only dilute hyposulphite solutions containing less than 4% of sodium hyposulphite. Other investigators, as Jellinek, have tried to avoid the decomposition losses by using 25 high current concentrations, whereby likewise a neutral solution of sodium bisulphite as catholyte and a solution of H₂SO₄ or common salt as anolyte were employed. In the best case hyposulphite 30 concentrations of scarcely 7% were obtained, the current yields did not exceed 30%. Another process consists in performing the electrolysis at low temperatures, preferably at 0—5° C., at any rate not essentially above 15° C. To prevent the 35 hyposulphite-ions to migrate to the anode, a part of the anolyte is caused to pass through the diaphragm into the cathode chamber. In this way concentrated hyposulphite solutions may be produced, but the current yields after having attained a concentration of 14%—15% of sodium 40 hyposulphite likewise amount only to 30%. Moreover the necessary strong cooling aggravates the technical performance of the process. Finally a process is based upon rapidly stirring the catholyte. This process permits the production of 45 concentrated sodium hyposulphite solutions whereby the current yield may even rise to 50%. But it has proved, that this rate of current yield does not satisfy, because in the manufacture of 50 hyposulphite solutions low current yields are connected with the formation of byproducts which remain dissolved in the catholyte and extraordinarily disturb the working up of these solutions.

55 In accordance with the present invention hy-

posulphites are produced in a technically simple cell and by a simple method attaining high current concentrations, for instance, 70—95%. The process comprises subjecting alkali metal- or zinc bisulphite-containing solutions with a pH of 4.5—6.0 as catholyte to electrolysis under rapid stirring; at current concentrations between 2 and 50 amperes per 100 ccm. catholyte, at temperatures between 0 and 50° C., preferably at 25—40° C. and cathodic current densities between 0.5 and 50, preferably at 2—20 amperes per 100 qcm. 5 surface of the cathode, whereby SO₂ is introduced into the catholyte so that the said acidity is maintained during the whole process of electrolysis, while simultaneously an aqueous solution 15 of an alkaline reacting alkali metal compound is introduced into the anode chamber and a substantial part of the anolyte is forced through the diaphragm into the cathode chamber.

The electrolyzing cell may be of optional construction so far as it permits to apply current concentrations up to 50 amperes per 100 ccm. catholyte, that is to say: the cathode chamber, the quantity of catholyte respectively, must be small in proportion to the charge of the cell with current. In the annexed drawing a cell of tubular construction is shown by way of example. In this drawing (1) represents a cylindrical vessel, which may consist of lead or silver, which is connected with the negative pole of the source of current. Within this vessel a clay tube (2), which is provided with a bottom, is arranged as a diaphragm in a distance of about 8 mm. from the cylindrical side of the vessel. Inside of the diaphragm a tube (3) is placed, which is connected with the positive pole of the source of current; it may be of lead, chromium-nickel-steel or graphite corresponding to the anolyte employed. The cell is closely shut by the rings (4) and (5) of rubber. By pipes (6) and (7) the solutions, which form or fill up the anolyte or the catholyte are introduced. By pipe (8) the developed oxygen at the anode and, in a given case, also a part of the anolyte leave the cell. Pipe (9) represents the overflow pipe for the catholyte. Around the vessel (1) there is arranged a cooling jacket (10). At the bottom of the vessel (1) a perforated ring (11) is provided, by which SO₂ may be finely divided which is introduced by pipe (12). 35 40 45

If this cell is charged with current, for instance, 50 so that a current density of 10 amperes per 100 qcm. is on the cathode, the current concentration at a distance of 8 mm. between diaphragm (2) and vessel (1) amounts to about 12 amperes per 100 ccm. of catholyte. When using higher or 55

lower current densities or varying the distance between cathode and diaphragm the rate of the current concentration may be readily shifted to higher or lower values.

5 According to the same principle cells of filter-presslike construction or any other form may be constructed, whereby diaphragms of porous rubber or any other flexible material may be used instead of clay diaphragms. Also the anode may 10 be constructed in form of a vessel or a chest provided with a cooler. By pipe (13) the cooling water is introduced leaving the apparatus by pipe (14). On the other hand, in certain cases, cooling of the cathode is superfluous, if the anode is 15 cooled.

These and many other variations are possible for the construction of a cell suitable for the present process.

The working of the cell may be as well periodically as continuously, that is to say, in the first case the cell is filled with the solutions, provided as anolyte and as catholyte, then electrolysis is effected; finally both, catholyte and anolyte are removed and replaced by fresh solutions, or the 25 catholyte alone is periodically replaced while the anolyte is continuously replaced; in the other case the corresponding solutions flow continuously as well through the cathode chamber as through the anode chamber while electrolysis is effected. As 30 catholyte solutions containing bisulphites of alkali metals or of zinc, but also solutions of neutral salts of these metals to which bisulphites are added or in which bisulphites are formed by introducing SO_2 , are used. The acidity, which is 35 measured by means of a glass-electrode is to be kept between $\text{pH}=4.5$ and $\text{pH}=6.0$; preferably between $\text{pH}=5.0$ and 5.5. This acidity corresponds to a mixture of bisulphite with 0-50% of sulphite. Up to the present day it was not known, 40 that the formation of hyposulphite depends so very much on the acidity of the catholyte. Hitherto a mixture of 95% of sodium bisulphite and 5% of sodium sulphite, the pH of which is about 5.0, and a mixture of 95% of sulphite and 5% of bisulphite, the pH of which is more than 7.0, 45 have been suggested as being equivalent. However, it has been found that the current yields in both cases are quite different. Under equal conditions there are obtained in the former case more than 90%, in the latter case scarcely 20%. It is 50 an essential characteristic of this invention that the acidity for the whole duration of the electrolysis is maintained between a pH of 4.5 and 6.0. Stirring of the catholyte may be effected in any convenient manner. A suitable method is 55 by pumping the catholyte with great speed through the cathode chamber along the cathodes. For this purpose a pump is arranged at the outside of the cell (not shown in the drawing). The liquid circulates through pipe (1) into the cathode chamber, leaving the latter by pipe (9), passing 60 a small intermediate vessel where gases may be given off and returns into the pump. SO_2 may be introduced into the catholyte not only by means of the perforated ring (11) but also from outside 65 the cell before or behind the pump in a mixing vessel.

Particularly advantageous, however, is stirring by means of a gas, which is inert toward the reagents of the process, such as CO_2 , N_2 or H_2 . This gas is introduced together with the SO_2 at the distributor (11). The movement of the catholyte in this case is so rapid that secondary reactions are practically avoided. Thereby moreover an 70 even distribution of the SO_2 on the whole quan-

75 tity of catholyte is obtained and a too sudden absorption in the neighbourhood of the distributor is prevented. In this manner local superacidification, which would reduce the current yield is easily avoided.

80 A further advantage of stirring with gases is the diminution of the quantity of liquid, which is present in the cathode chamber. Thus, the current concentration may be increased to high values.

85 The cathodic current density may vary between wide limits, but is not allowed to surpass a certain value, as otherwise formation of hydrogen and secondary reactions would take place. This boundary current density differs according to the 90 form of the surface of the cathode and to the intensity of stirring. In general, however, 50 amperes per 100 qcm. should not be surpassed. Cathodes the effective surface of which consists in an arrangement of thin wires were found to 95 be particularly advantageous. Thin wires in this case, are wires of a diameter of about 0.1-2 mm., preferably of 0.1-0.5 mm. The wires are arranged in such a manner, that intervals are formed between the single wires, so that the catholyte 100 passes through and thus comes into intimate contact with the surface of the wires. The intervals between the wires or, if the wires are net-like arranged, the meshwidth, are about 0.1-0.5 mm. In the drawing, the wire-net is represented 105 by the dotted line (15). It is soldered to the vessel (1).

110 The temperature of the catholyte is not restricted to temperatures below 15° C., but may rise up to 50° C. Preferably the process may be 115 carried out at 25-40° C. Since no cooling or only cooling with simple means is necessary, this process is cheaper than the usual ones. Also, on account of the lower viscosity of the solution stirring or moving of the electrolyte is more effective.

120 Alkaline reacting alkali metal compounds suitable for effecting the process are solutions of alkali metal hydroxides or carbonates. It may, however, be advantageous to use a solution of neutral alkali metal sulphite.

125 The transport of a substantial part of the anolyte through the diaphragm into the cathode chamber can be effected by means of super-pressure in the anode chamber or by reduced pressure in the cathode chamber or also by combining the two methods. This can be effected by 130 keeping the level of the liquid in the anode chamber above the level of the liquid in the cathode chamber. Further, the transport is favored by the stirring gas, which reduces the specific weight 135 of the liquid in the cathode chamber and thus also serves for facilitating the transport. In this manner the diffusion of hyposulphite anions to the anolyte is avoided, whereby an important increase of the yield is attained.

140 The invention is especially illustrated by the following examples without being restricted thereto.

Example 1

145 In a tubular cell as described above and being provided with an anode of chromium-nickel-steel and a cathode of silverplate, a 23% sodium-bisulphite solution as catholyte is electrolyzed while 150 using a cathodic current density of 6 amperes per 100 qcm. and a current concentration of 10 amperes per 100 ccm. of catholyte. By introducing SO_2 into the catholyte the pH is kept at 5.2-5.5 for the whole duration of the electrolysis. Stirring of the catholyte is effected by rapid circulation by means of a pump. The temperature is 155

5 maintained at 30-33° C. by cooling the cathode with cold water. A 15% solution of sodium hydroxide is continuously introduced into the anode chamber. The hydrostatic pressure in the anode chamber is so adjusted, that it is higher than the hydrostatic pressure in the cathode chamber so that an essential part of the anolyte is pressed through the diaphragm into the cathodic chamber. In consequence of this transport the volume 10 of the catholyte increases for about 50% until a 14-15% hyposulphite solution is attained. If at this state electrolysis is interrupted, the medium current yield calculated on hyposulphite is 73%.

15 If now between vessel (1) and diaphragm (2) a silver wire net of a meshwidth of 2 mm. and a wire-thickness of 0.25 mm. is arranged in such a manner that the net at the upper and lower end is soldered to the vessel the current yield rises to 78%.

20 A similar effect is obtained if in the original arrangement with the silver plate cathode stirring is not effected by pumping, but by passing through an inert gas, as CO_2 , N_2 , H_2 . The current yield in this case amounts to 80%.

25 If finally the use of gas stirring is combined with the employment of the wire-net-cathode as above described, the current yield rises to 90%.

Example 2

20 In an electrolytic cell as described above and in the form of a filter press cell, which is divided into anode and cathode chambers by means of a porous rubber plate as the diaphragm, in which cell the anode consists of a lead plate and the cathode is a silver wire net, a 16% sodium bisulphite solution as the catholyte is subjected to electrolysis at 15° C. while using a 17% sodium sulphite solution as the anolyte, a cathodic current density of 14 amperes per square decimeter and a current concentration of 8 amperes per 40 100 ccs. of catholyte. Anolyte and catholyte pass through the cell continuously, that is the anolyte passes through the anode chamber and the catholyte passes through the cathode chamber. During the electrolysis carbon dioxide, hydrogen or 45 nitrogen is introduced at the lower part of the cathode chamber for stirring the catholyte. By adding SO_2 to the said stirring gases the necessary SO_2 is conducted to the catholyte while simultaneously establishing the desired degree of 50 acidity. Now, by causing the acidity to correspond to different pH-values by the corresponding addition of SO_2 , and taking care that always at the same time the same quantity of catholyte 55 leaves the chamber by fixing the rate of flow of the catholyte, there is obtained at a pH-value of 6.8 a 3% solution with 16% current yield, at a pH-value of 6.5 a 9.2% solution with 60% current yield, at a pH-value of 5.4 a 16.5% solution 60 with 91% current yield, at a pH-value of 4.25 a 12% solution with 70% current yield, at a pH-value of 3.5 a 5% solution with 26% current yield. The pH-values in this case relate to values measured by means of the glass electrode at 20° 65 C. According to the intensity of stirring, the values differ somewhat in such a manner that they are more favorable with more vigorous stirring and less favorable with less good stirring. The bath tension differs according to the various 70 degrees of acidity. It is the lower the more acid is the catholyte.

If the temperature of the catholyte is fixed to 43° C. under otherwise the same conditions as indicated there is obtained at a pH-value of 6.1 a 15% hyposulphite solution with 80% current

yield, at a pH-value of 5.6 a 16% solution with 90% current yield, at a pH-value of 4.85 a 15% solution with 85% current yield. The bath tension is about 10-15% lower than at 15° C.

All conditions not specifically mentioned in the foregoing example are identical with those given in Example 1, especially a substantial part of the anolyte is forced by hydrostatic pressure through the diaphragm into the cathode chamber.

This application is a continuation in part to 10
application Ser. No. 77,641, filed May 2, 1936.

We claim:

1. Process for preparing water soluble hypo-sulphites which comprises electrolyzing an aqueous bisulphite-containing solution at a current 15 concentration between about 2 and about 50 amperes per 100 ccm. catholyte, at a temperature between about 0 and about 50° C., at cathodic current density between about 0.5 and about 50 amperes per 100 qcm. cathode surface, while 20 maintaining the acidity of the catholyte during the electrolysis at a pH of between about 4.5 and about 6.0 by introducing sulphur dioxide into the catholyte, and forcing a substantial part of the anolyte through the diaphragm into the cathode 25 chamber, said anolyte consisting of an alkaline reacting aqueous solution of an alkali metal compound, while rapidly stirring the catholyte.

2. Process for preparing water soluble hypo-sulphites which comprises electrolyzing an aqueous bisulphite-containing solution at a current concentration between about 2 and about 50 amperes per 100 ccm. catholyte, at a temperature between about 0 and about 50° C., at cathodic current density between about 0.5 and about 50 amperes per 100 qcm. cathode surface, while maintaining the acidity of the catholyte during the electrolysis at a pH of between about 4.5 and about 6.0 by introducing sulphur dioxide into the catholyte, stirring the catholyte by means of a gas inert to the reagents of the process, and forcing a substantial part of the anolyte through the diaphragm into the cathode chamber, said anolyte consisting of an alkaline reacting aqueous solution of an alkali metal compound.

3. Process for preparing water soluble hypo-sulphites which comprises electrolyzing an aqueous bisulphite-containing solution at a current concentration between about 2 and about 50 amperes per 100 ccm. catholyte, at a temperature between about 0 and about 50° C., at cathodic current density between about 0.5 and about 50 amperes per 100 qcm. cathode surface, while maintaining the acidity of the catholyte during the electrolysis at a pH of between about 4.5 and about 6.0 by introducing sulphur dioxide into the catholyte, and forcing a substantial part of the anolyte through the diaphragm into the cathode chamber, said anolyte consisting of an alkaline reacting aqueous solution of an alkali metal compound, while rapidly stirring the catholyte, the cathodes consisting of thin wires having a diameter of about 0.1-2 mm. being arranged at intervals of about 0.1-0.5 mm.

4. Process for preparing water soluble hypo-sulphites which comprises electrolyzing an aqueous bisulphite-containing solution at a current concentration between about 2 and about 50 amperes per 100 ccm. catholyte, at a temperature between about 0 and about 50° C., at cathodic current density between about 0.5 and about 50 amperes per 100 qcm. cathode surface, while maintaining the acidity of the catholyte during the electrolysis at a pH of between about 4.5 and about 6.0 by introducing sulphur dioxide into the

catholyte, stirring the catholyte by means of a gas inert to the reagents of the process, and forcing a substantial part of the anolyte through the diaphragm into the cathode chamber, said anolyte consisting of an alkaline reacting aqueous solution of an alkali metal compound, the

cathodes consisting of thin wires having a diameter of about 0.1-2 mm. being arranged at intervals of about 0.1-0.5 mm.
